DESIGN FOR A DOLL

Helen A. Smiley, Philadelphia, Pa.

Application November 4, 1944, Serial No. 116,141

Term of patent 14 years

(Cl. D34—15)

To all whom it may concern:

Be it known that I, Helen A. Smiley, a citizen of the United States, residing at Germantown, Philadelphia, in the county of Philadelphia and State of Pennsylvania, have invented a new, original, and ornamental Design for a Doll, of which the following is a specification, reference being had to the accompanying drawing, forming part thereof.

I claim:

The ornamental design for a doll, as shown.

HELEN A. SMILEY.
